right now, right outside of New Mexico. She's right about the personal connection to the place, but I think it's more about the people. I think it's more about the people that are there, the people that are involved in the community, the people that are involved in the church, the people that are involved in the school, the people that are involved in the business community. I think that's what's important about the place.

UNITED STATES PATENT OFFICE

2,521,873.

IMPEDANCE MATCHING DEVICE FOR WAVE GUIDES FOR ANTENNA SYSTEMS

Randal McG. Robertson, Cambridge, Mass., as signor, by mesne assignments, to the United States of America as represented by the Secretary of War

Application October 30, 1944, Serial No. 560,973

1

This invention relates to directive antenna systems for transmission and reception of high frequency radio waves, and more particularly to antenna arrays using a variable-width wave guide.

The present invention is directed to an arrangement for maintaining a desirable degree of power transfer between a wave guide of fixed width and a wave guide of variable width. This device depends upon the discovery that a satisfactory impedance match can be maintained provided that the wave guide of fixed width is moved so that it remains centered with respect to the wave guide of variable width. The invention will more readily be understood from the following description with reference to the accompanying drawings in which:

Fig. 1 is a back elevation view partly broken off of an arrangement according to this invention for matching a scanning antenna to a wave guide leading to a transmitting and receiving system and

Fig. 2 is an enlarged cross-sectional view of the same along the line 2-2 of Fig. 1.

Referring to the drawings, a lower narrow wall member 6 of wave guide 5 is fixed in position upon a fixed front plate 10 which carries an array of dipoles (not shown). An upper narrow wall member 1 of wave guide 5 reciprocates in a vertical direction, as driven by the scanning mechanism (not shown), and is carried by a movable back plate 11. A rack 12 (Fig. 2) is mounted on plate 11 and another rack 13 is mounted upon a bracket 14 which is carried on the front plate 10 near one of its longitudinal extremities. A pinion, or preferably a pair of pinions 15 and 16 are arranged between and are adapted to engage racks 12 and 13 and are mounted in a small frame 17. It will be seen that the movement of the rack 12 as a result of the scanning motion impressed upon the back plate 11 will impress upon the frame 17 a motion having half the amplitude of the driving motion. This motion is then impressed upon the fixed-width wave guide 18 by means of an arm 19, projecting from the frame 17, which is fastened to the wave guide 18 by means of a pivot connection. The arm 19 is preferably in the form of a bar or tongue adapted to fit into a groove or slot 20 located substantially mid-way of the width of the frame 17 and desirably between the pinions 15 and 16. It will be obvious, however, that the exact location and manner of mounting of the arm 19 on the frame need not be limited to this particular structure.

The wave guide 18, shown broken away at 21

2

to simplify the illustration, may be folded back on itself and, at a suitable place in the portion of the wave guide thus folded in back of the antenna array, a wobble joint or other suitable connection is provided in a well-known manner in order to permit the wave guide 18 to follow the motion impressed upon it by the frame 17. Because the motion of the frame 17 has exactly half the amplitude of the motion of back plate 11, the frame 17, after proper setting, will automatically maintain the fixed-width wave guide 18 centered with respect to the variable-width wave guide 5 which feeds the antenna array.

If desired, a suitable coupling member 22 may be mounted in known manner on the end of the fixed-width wave guide 18 and the arm 19 may be pivotally connected to the coupling member so that the movement of the arm 19 will be impressed on the coupling member 22 and the wave guide 18.

While a preferred embodiment of the present invention has been illustrated and described, it will be understood this is capable of modification and improvement without departing from the spirit of the invention. Therefore it is not desired that the scope of the invention be limited to the precise details set forth.

What is claimed is:

What is claimed is:

30 1. A wave guide system comprising a wave guide of fixed width, a variable width wave guide having a fixed side wall and an opposite movable side wall, and means for maintaining the fixed-width and variable-width wave guides mutually centered comprising a rack member rigidly associated with said fixed side wall, a second rack member rigidly associated with said movable side wall, pinion means located between said racks and engageable therewith, and means connecting said pinion means and said fixed-width wave guide, a movement of said second rack member causing movement of said pinion means and of said fixed-width wave guide in the same direction but of half the amplitude of movement of said movable side wall, thus maintaining the fixed-width and variable width wave guides mutually centered.

35

40

45

50 2. A wave guide system including a fixed width wave guide, a variable width wave guide coupled to said fixed width wave guide, said variable width wave guide comprising two L-shaped members so disposed and arranged as to define an area therebetween, means for displacing one of said members with respect to the other of said members to vary a dimension of said area, and means including a mechanical linkage between

said one member and said fixed width wave guide and responsive to said displacement to move said fixed width wave guide with respect to said other member in the same direction and through half the distance of said displacement of said one member for maintaining said fixed and said variable width wave guides mutually centered whereby a satisfactory impedance match is obtained.

3. A wave guide arrangement for impedance matching a fixed width wave guide to a variable width wave guide comprising a fixed width wave guide, a variable width wave guide coupled to said fixed width wave guide and including a fixed wall and a movable wall, means for displacing said movable wall to vary a dimension of said variable width wave guide, and mechanical linkage means coupling said fixed width wave guide to said movable wall and responsive to the displacement of

said movable wall to displace said fixed width wave guide in the same direction through half the distance of said displacement of said movable wall to maintain said fixed width and variable width wave guides mutually centered.
